SOAP TRAY

Eugene Y. Guthmann, Philadelphia, Pa.

Application December 20, 1954, Serial No. 33,609

Term of patent 14 years

(Cl. D4—3)

Fig. 1 is a view in perspective of a soap tray showing my new design;

Fig. 2 is a top plan view of the soap tray;

Fig. 3 is a side elevational view of the soap tray;

Fig. 4 is a front elevational view of the soap tray, and

Fig. 5 is a rear elevational view of the soap tray.

I claim:

The ornamental design for a soap tray, substantially as shown.
